US00D668661S

(12) **United States Design Patent**
Norfolk

(10) **Patent No.:** **US D668,661 S**
(45) **Date of Patent:** **** Oct. 9, 2012**

(54) **PROTECTIVE COVER FOR TABLET COMPUTER**

(76) Inventor: **Brian K. Norfolk**, Everett, WA (US)

(**) Term: **14 Years**

(21) Appl. No.: **29/391,607**

(22) Filed: **May 11, 2011**

(51) **LOC (9) Cl.** **14-02**

(52) **U.S. Cl.** **D14/440**

(58) **Field of Classification Search** D14/439, D14/440, 345, 341-344, 346, 371, 125-129, D14/327; 206/320, 576, 305, 215, 232, 524, 206/425, 472, 224, 312, 387.13, 307, 387.1, 206/756; D3/286, 283, 295, 273, 303, 247, D3/215, 245, 232, 900, 249, 201, 276, 294, D3/301; 224/929; 708/110; 190/109, 100, 190/119, 901; 361/683, 725, 681, 686, 679; 229/87.5, 67.1, 800; 220/522, 4.23; 345/169, 345/104, 156, 168, 173, 179, 672, 174; 150/147, 150/135; 402/2, 70-78, 500-502; 281/45, 281/38, 31, 29, 19.1, 34; D19/26, 27, 33, D19/75, 86, 22, 90, 59, 60, 78, 83; D18/7; 383/97, 4, 110; 178/18.03, 18.01; 349/12; 428/332; D6/632, 407; 248/458

(57) **CLAIM**

I claim the ornamental design for a protective cover for tablet computer, as shown.

DESCRIPTION

FIG. 1 is a front perspective view of a protective cover for tablet computer;

FIG. 2 is a rear perspective view thereof;

FIG. 3 is a front view thereof;

FIG. 4 is a rear view thereof;

FIG. 5 is a right side elevation view thereof;

FIG. 6 is a left side elevation view thereof;

FIG. 7 is a top plan view thereof; and,

FIG. 8 is a bottom plan view thereof.
